UNITED STATES PATENT OFFICE.

YUSUKE TAMAMURA, OF ASHIO, JAPAN.

DIFFERENTIAL CLIP FOR AERIAL ROPEWAYS, &c.

No. 850,504.

Specification of Letters Patent.

Patented April 16, 1907.

Application filed January 4, 1907. Serial No. 350,846.

To all whom it may concern:

Be it known that I, YUSUKE TAMAMURA, a subject of the Emperor of Japan, and a resident of Ashio, in the Province of Shimozu, Japan, with a post-office address at Ashio, Province of Shimozu, Japan, have invented certain new and useful Improvements in Differential Clips for Aerial Ropeways and the Like, of which the following is a specification, reference being had to the accompanying drawings, forming a part hereof.

My invention relates to clips or grips for engaging the hauling-rope in aerial ropeways, telpherage systems, and the like, and particularly to those grips or clips which are operated by gravity through the weight of the carriage or the carriage and its contents.

The object of my invention is to provide a novel and efficient grip operated in a different manner from those heretofore used and by its nature more readily capable of adaptation to various conditions met with in such systems. I am aware that gravity-operated grips have been known in the art; but a disadvantage of this form of grip is that as ordinarily constructed the hauling-rope is apt to be destructively compressed.

In this invention, which I term a "differential clip," I make use of the advantages to be had from lever-arms of unequal length, and by varying the difference in length of such lever-arms I am able to design my grip or clip for a wide range of compression on the hauling-rope.

In the drawings, Figure 1 shows my clip or grip applied to a carriage on a double-rope system or one in which the carriage runs upon a track-rope or other track and is drawn by a hauling-rope, usually below the track or track-rope. Fig. 2 is an enlarged side view of my clip or grip in a position taken at the uncoupling-rails. Fig. 3 is a plan view of the clip or grip on the same scale as Fig. 2. Fig. 4 is a modification of the clip or grip for a double-rope system, while Figs. 5 and 6 are modifications applicable to a single-rope system.

In Fig. 1, which broadly illustrates the invention, 1 is the track or track-rope of a double-rope system; 2 is a carriage-wheel or one of a pair of carriage-wheels running on and hung upon the track or track-rope and journaled on an axle in the carriage frame or hanger 3. The hanger 3 is hitched to the long and short arm members 5 and 6 of the clip or grip by a clip-pin 4, upon which pin

3, 5, and 6 are free to turn. The free end of the member 5 is rotatably connected on the head of the hook of the receptacle or car by a pin 11, rotatably fixed into a cross-pin 10, 60 bossed into the head of 14. The free end of the member 6 is likewise connected to a pin 9, and thus hinged in a pin 8, (see Fig. 2,) which is bossed into 14, but is free to move longitudinally. At the end of the pin 10 is a 65 small wheel 13. 12 is one of a pair of small wheels journaled on the ends of a T-shaped carrier rigidly connected to and movable with the sliding pin 8.

The operation of the grip or clip will be 70 more clearly understood by reference to Fig. 2, in which the members 5 and 6 are shown in close approximation and with the jaws of the clip open. It will be seen, since the lever-arms of the grip 5 and 6 are different in 75 length, that a common vertical movement of the free ends of these lever-arms will necessarily cause the levers to describe different angular distances and the difference in angular travel of the members 5 and 6 will be a 80 function of their difference in length. In other words, the arms in moving a given vertical distance move over angles of which this vertical distance is a sine function, and since the radii are different, the angles of 85 travel must necessarily vary. Thus it will be seen that the effect of the weight of the supporting member 14 or of the weight carried by 14 will be to cause the jaws of the grip to be approximated with a force which 90 is a function of the difference in the length of the lever-arms and of the applied weight at their free end. Obviously by modifying the difference in length of the arms any desired degree of grip or compression on the hauling- 95 rope can be attained.

In Fig. 2 uncoupling-rails 15 and 16 are indicated engaging, respectively, the wheel 13 and the pair of wheels of which 12 is one. These uncoupling-rails are so disposed at a 100 station as to relieve the clip members from the weight of the hook 14 and the load sustained by it by lifting the member 14. This, as seen in Fig. 2, decreases the angle between 5 and 6 and opens the jaws of the clip, so that 105 the carriage may be completely freed from the hauling-rope. Obviously the supporting-rails 15 and 16 are suitably inclined at their ends if the track or track-rope is horizontal or otherwise disposed if the track or 110 track-rope is inclined, so as to properly engage the wheels 13 and 12-12.

In Fig. 3 the plan view of the clip or grip, the wheels 12 12', and their supporting-carrier 8' are shown, and also the rope 7, held between the jaws of the clip.

Fig. 4 shows a modification of the clip or grip for a double-rope-way system, 3 being the hanger and the other parts being designated by corresponding numbers to those employed in Figs. 1 and 2, as 5' and 6' instead of 5 and 6. It will be seen that the short member 6' is hinged directly to the hanger 3 by a pin 9', while the longer member 5' is hinged by a pin 11' to a pin 10', the latter bossed into and capable of longitudinal movement in the lower end of the hanger 3. The carriage member 14' instead of being attached to the free ends of the levers, as in Figs. 1 and 2, is journaled on the axis of the clip members. Instead of the wheels 13 and 12, supported at or near the free ends of the clip members, in this case there are a pair of wheels, one of which is shown at 12', journaled upon extensions of the clip-pin itself. Therefore only a single uncoupling-rail is necessary to relieve the clip members of the weight upon 14'. In other words, the clip is reversed. Though this design is more simple than the one just described, slipping may occur on steep grades whenever in the case of a track-rope there is sufficient sag to allow part of the weight to be taken by the hauling-rope, and the design is best adapted for use in those cases where the track or track-rope is sufficiently rigid.

In Figs. 5 and 6 a modification is shown for use where there is no track or track-rope, but simply a hauling-rope. The action of the clip or grip is identical in principle with that already shown. On a main axle 19 through the head of the member 14 is journaled a supporting-ring 20, to which is hinged the short clip member 6'' by a pin 9'', and to a sliding pin 10'' is hinged the member 5'' by a pin 11''. It will be noticed that the jaws of the clip engage the rope from above. On the axle 19 is also journaled a member 22, carrying at its upper branched end, as shown in Fig. 6, two wheels 12'' 12''. There is a handle 21 on the supporting-ring by which the clip may be rotated on the axle 19. The bracket 22 is also capable of rotation on 19 through a certain angular distance in one direction, but in the other direction must revolve with the clip. In other words, it is free to move at its axis independent of the clip in one direction only. As shown in Fig. 6, an arm 17, carried by the lower extension of the bracket member 22, engages a spring which tends to force the handle 21 and the member 22 into alignment and to bring the axes of the wheels 12'' 12'' into a position at equal distances from the hauling-rope.

As shown in Fig. 6, when the carriage approaches an uncoupling-rail, as 15'', the weight of the car will be taken by the rail

and the clip will open by the weight of its parts. Similarly, in attaching a car to the hauling-rope the car can be run out on the rail 15'' and the clip turned by the handle 21 into position for engaging the rope, and as the wheels leave the supporting-rail 15'' the weight of the load will cause the clip to engage the rope. The action of the spring will then draw the supporting-bracket 22 into line with the handle 21 or into its normal position, so that the wheels 12'' 12'' will not be in the way when the grip runs over supporting-pulleys of the ropeway.

I do not confine myself to the specific construction shown, since it is obvious that various modifications could be used in practice without departing from the spirit of the invention. While I have shown several methods of applying the supported weight to the clip system, both at the axis of the clip and at the free-ends of the clip-levers, it is obvious that other methods of attaching the weight to the clip and of attaching the traveling carriage or trolley could be used with equal efficiency, still retaining all of the advantages to be had by the use of the differential lever-arms of the clip.

Having described my invention, what I claim is—

1. In apparatus of the class described, a grip formed of two jaw-levers of different length flexibly connected to the carriage in such manner as to be moved differential angular distances by a common vertical movement of their free ends.

2. In apparatus of the class described, a grip formed of two levers having a common axis and their shorter ends formed into jaws and means for causing said levers to move differential angular distances for a given common vertical movement of their longer ends.

3. In apparatus of the class described, a grip formed of two mutually-journaled jaw-levers of differential length and means for moving said levers an unequal angular distance for a given common vertical displacement of their free ends.

4. In apparatus of the class described, a rope-grip formed of two levers having a common axis, a jaw formed on one end of each lever, and means for causing said levers to move in the same direction differential angular distances when their free ends are displaced vertically a common distance.

5. In apparatus of the class described, a jaw formed by the short ends of two levers of unequal length having a common axis and a flexible connection of the carriage-sustaining member to the free ends of such differential arm.

6. In apparatus of the class described, a supporting member, a lever hinged to the upper part thereof, a second lever hinged to the upper part thereof by an axis capable of motion normal to its length, a common fulcrum

for said levers and jaws formed in said levers beyond said fulcrum.

7. In apparatus of the class described, a supporting member, a lever hinged to the upper part thereof, a second lever hinged to the upper part thereof by an axis capable of motion normal to its length, a common fulcrum for said levers and jaws formed in said levers beyond said fulcrum and means for relieving 5 said levers of the weight of said supporting member at terminal stations.

8. In apparatus of the class described, a clip or grip for rope composed of two clip members having a common axis and lever-arms of different length, a supporting member 15 flexibly connected to the free ends of such lever-arms, and means for relieving such lever-arms of the weight of such supporting member at terminal stations.

9. In apparatus of the class described, a clip or grip for engaging a rope composed of two clip members having a common axis and lever-arms of different length, and means for 20

operating said clip by the differential action of the sustained weight on the free ends of 25 such lever-arms.

10. In a rope-grip, jaws formed by the ends of mutually-hinged levers of unequal length and means for causing the free ends of said levers to move equal distances in a common direction, but different angular distances. 30

11. In a rope-grip, a pair of mutually-hinged levers each provided with a jaw, said jaws respectively approximated, and means 35 for causing said levers to move differential angular distances under the effect of a weight applied to their free ends.

Signed by me at the American Embassy at Tokyo, Japan, this 12th day of November, 40 1906.

YUSUKE TAMAMURA.
